(57) **CLAIM**

The ornamental design for a putter grip, as shown and described.

DESCRIPTION

FIG. 1 is an isometric top view of a putter grip showing my new design;

FIG. 2 is a front view of the putter grip;

FIG. 3 is a rear view of the putter grip;

FIG. 4 is a left side view of the putter grip;

FIG. 5 is a top view of the putter grip;

FIG. 6 is a bottom view of the putter grip; and,

FIG. 7 is a cross-sectional view taken along line 7-7 of FIG. 1 of the putter grip.

The broken lines shown on the drawing views form no part of the claimed design.
